UNITED STATES PATENT OFFICE

OSCAR W. ANDERSEN, OF OAK PARK, ILLINOIS, ASSIGNOR TO PETTIBONE MULLIKEN COMPANY, A CORPORATION OF NEW YORK

DREDGE AND THE LIKE

Application filed March 26, 1927. Serial No. 178,756.

This invention relates to improvements in dredges and the like, and more especially to suction dredges of the type having a suction nozzle adapted to be raised and lowered.

3 The invention relates more particularly to a dredge of the character described, having a traveling screen or chain traversing the mouth of the suction nozzle, in order to exclude objects of undesired size. The traveling screen may take the form of a chain with separated links, thus forming a sieve or screen.

One of the objects of my invention is the provision of means adjacent the nozzle to prevent stones and other large objects from interfering with the travel and operation of the chain. The details of such means and apparatus will be described and explained more in detail hereinafter.

20 I also provide improved means for carrying the chain adjacent the nozzle to lessen friction where the chain traverses the mouth of the nozzle. Instead of a stationary track at this point with its consequent friction, I 25 provide wheels to carry the lower bight of the chain, thus reducing friction to a minimum. The wheels that I use are disk wheels so that there are no spokes, or other projecting parts on them that can be caught or engaged by stones or other objects to lock them and prevent their free rotation. The wheels being disk wheels, also serve to exclude stones, and other objects, from the space between the wheels, thus assisting in preventing any undesired objects from entering the space adjacent the nozzle where they might become caught by the chain and interfere with its proper operation.

Another feature of my invention is the 40 provision of improved means for carrying the wheels at the end of the arm which carries the suction pipe. The wheels are carried by a shaft mounted on the end of the arm. Improved means for carrying the nozzle itself also comprise a fitting or clamp surrounding the shaft between the wheels, such fitting or clamp serving to support the nozzle from the shaft.

Another feature of my invention is the 50 provision of improved, replaceable chain

track carried by the arm and improved means for protecting and guarding the chain.

Other features and advantages of my invention will appear more fully as I proceed with my specification.

In that form of device embodying the features of my invention shown in the accompanying drawings, Fig. 1 is a view in side elevation of the arm carrying the suction pipe, with the suction nozzle at the end, Fig. 2 is a view taken as indicated by the line 2 of Fig. 1, Fig. 3 is a view in perspective of the end of the arm, Fig. 4 is a view taken as indicated by the line 4 of Fig. 1, Fig. 5 is a top plan view of a part of the chain screen, Fig. 6 is a view in front elevation of the end of the arm and suction nozzle, and Fig. 7 is a view of the same in side elevation with a part of the end of the arm removed.

As shown in the drawings, 10 indicates a suitable arm preferably made up of truss members, struts, and braces, to give the desired strength and rigidity. The upper end of the arm 10 is pivoted at 10^a so that its lower end may be raised and lowered if desired. The means for raising and lowering the lower end of the arm are not shown as they are in common use and form no part of the present invention.

The arm 10 carries the usual suction pipe 11 and suitable means (not shown) are provided at the upper end for sucking water and material to be dredged, upwardly through this pipe in the usual manner. The lower end of this pipe 11 terminates in a squared (in cross section) nozzle 12 having a mouth 13 opening downwardly and rounded at the sides as indicated by 13^a.

14 indicates in general the travelling screen chain formed of cross members or shafts 14^a suitably joined by separated links 14^b so that the chain forms virtually a screen or sieve. The bars 14^a are provided at their ends with the rollers 14^c to lessen friction in the travel of the chain on the stationary tracks. The chain is also provided with projecting hooks, claws or fingers 14^d which serve to dig into the place to be excavated, to loosen up, agitate, and stir up the material, thus permitting the suction to more readily carry it away.

These claws, hooks, or fingers 14^d also serve to engage and remove away from the mouth of the nozzle objects which are too large to enter. These objects are thrown to one side by these hooks, or else carried upwardly on the chain and dumped at the upper end as the chain passes over the upper sprocket.

The upper end of the chain or bight of the chain is carried by a driving sprocket 15 which may be driven in any suitable manner as, for example, by means of the gears or pinions 16 and 17. Any suitable motor or engine (not shown) may be used for driving these wheels.

15 The lower end of the arm 10 is provided with the two triangular side plates 18 and these carry the transversely mounted shaft 19 which is held to the edges of the plates by means of the clamping members 20. The shaft 19 carries the two solid or disk wheels 21, 21 which lie between the sides of the nozzle 12 and the plate 18. 21^a indicates the periphery or tread of the wheel 21, and 21^b indicates a flange on the outside of this tread.

20 25 The chain 14 is adapted to lie on the treads 21^a and be retained thereon by means of the flanges 21^b. The wheels 21 are of such a size and so located that the periphery 21^a will be substantially concentric with the rounded 30 sides 13^a of the mouth of the nozzle, lying slightly beyond the same, so that the chain 10, in passing over the wheels 21 will lie across the mouth of the nozzle and close thereto, to serve as a screen or sieve for the mouth and 35 prevent entrance therethrough of undesired objects.

40 The nozzle 12 is supported and held securely in position by means of the clamp 22 attached to its upper surface and surrounding the shaft 19. It will be seen, therefore, that the weight of the end of the nozzle is carried by the shaft 19, the ends of which are firmly attached and secured to the end of the arm 10.

45 45 The upper reach of the chain 14 is adapted to be supported on the arm 10 on the removable and detachable track members 23 in the form of angle irons. These track members 23 are mounted on members of the arm 50 10 by means of the rivets 24 as shown in Fig. 4, so that they can be removed from the arm 10 for replacement or repair without dismantling the arm itself. Similarly, the lower reach of the chain is carried on angle iron 55 track members 25 which are also removable from the arm members 10. It is to be understood, that in normal operation, the upper reach of the chain travels upwardly and the lower reach downwardly.

60 60 It is to be noted that the arm 10, being made of the usual truss or bridge construction, is substantially square in cross section and hollow, carrying the suction pipe 11 in its interior. At its lower end however, near 65 the mouth of the nozzle, the arm is closed by

a square diaphragm or plate 26, provided with a central aperture large enough to accommodate the suction pipe 11. It will be seen that this diaphragm or plate 26 substantially fills the space in the arm between the upper and lower reaches of the chain. The side edges of the diaphragm or plate 26 meet the rear edges of the triangular plates 18 (see Fig. 3). 27 indicates a curved apron, or guard plate extending from the upper edge of the diaphragm 26 forwardly and then curved downwardly until its lower edge 27^a meets the upper edge of the mouth 13 of the nozzle. 28 indicates a flat plate extending rearwardly from the rear edge of the mouth of the nozzle and lying just above the lower reach of the chain 14. This plate 28 extends rearwardly from the nozzle until it meets the lower edge of the diaphragm 26 and then is continued and extended upwardly through substantially the entire length of the arm 10 lying just above the lower reach of the chain 14. The curved plate or apron 27 is held in position by means of the angle irons 27^b and is of sufficient width so that it substantially fills the space between the treads 21^a of the two wheels 21 (see Fig. 2). Its curvature is substantially the same as the curvature of these two treads and concentric with the same, but it lies slightly inside of the tread so that the chain 14 in passing over the wheels will lie close to the plate 27 but not in contact with it.

65 It will be seen that the plates 26, 27, 18, and the lower end of the plate 28, taken together with the solid disk wheels 21, form virtually a closed box or housing around the nozzle 12, thus effectively preventing any stones or other undesired objects from getting in between the chain and wheels, or wheels and nozzle, or chain and nozzle, where they would catch, or jam, or interfere with the smooth working of the parts. Similarly, the plate 28, being extended upwardly through substantially the entire length of the arm 10 and lying above the chain 14, prevents any stones or other undesired objects, from riding on top of the lower reach of the chain, where they would cause damage or interference with the movement of the chain.

70 70 While I have shown and described certain embodiments of my invention, it is to be understood that it is capable of many modifications. Changes, therefore, in the construction and arrangement may be made without departing from the spirit and scope 115 of the invention as disclosed in the appended claims, in which it is my intention to claim all novelty inherent in my invention as broadly as possible in view of the prior art.

75 75 What I claim as new, and desire to secure by Letters Patent, is:

1. In a suction dredge of the character described; an arm adapted to be raised and lowered; a suction pipe carried in the interior of said arm and terminating in a noz-

zle with a mouth at the lower end of the arm, a chain screen carried by the arm and extending across the mouth of the nozzle; and means to prevent stones from being caught between the chain and the nozzle, 5 said means including a diaphragm in the arm a short distance back of the mouth of the nozzle surrounding the suction pipe and substantially filling the space in the arm between the two reaches of the chain. 10

2. In a suction dredge of the character described; an arm adapted to be raised and lowered; a suction pipe carried in the interior of said arm and terminating in a nozzle with a mouth at the lower end of the arm, a chain screen carried by the arm and extending across the mouth of the nozzle; and means to prevent stones from being caught between the chain and the nozzle, 15 said means comprising a diaphragm in the arm a short distance back of the mouth of the nozzle surrounding the suction pipe and substantially filling the space in the arm between the two reaches of the chain, and a 20 curved plate extending from the upper edge of said diaphragm beneath the chain to the upper edge of the mouth of the nozzle.

3. In a suction dredge of the character described; an arm adapted to be raised and lowered; a suction pipe carried in the interior of said arm and terminating in a nozzle with a mouth at the lower end of the arm, a chain screen carried by the arm and extending across the mouth of the nozzle; and means to prevent stones from being caught between the chain and the nozzle, 35 said means comprising a diaphragm in the arm a short distance back of the mouth of the nozzle surrounding the suction pipe and substantially filling the space in the arm between the two reaches of the chain, and a 40 curved plate extending from the upper edge of said diaphragm beneath the chain to the upper edge of the mouth of the nozzle, and 45 another plate extending from the rear edge of the mouth of the nozzle to the lower edge of said diaphragm.

4. In a suction dredge of the character described; an arm adapted to be raised and lowered; a suction pipe carried on the inside of said arm and terminating in a nozzle with a mouth near the lower end of the arm, said nozzle being substantially square in cross section and the side edges of the same being 55 rounded; a chain screen carried by said arm and having its lower bight mounted on wheels adjacent the sides of the nozzle whereby the chain is adapted to move across the mouth of the nozzle; and means for preventing stones from lodging between the chain and the nozzle, said means comprising side plates on the arm, a diaphragm in the arm surrounding the suction pipe and extending between the two reaches of the 60 chain, a curved plate extending from the 65

upper edge of the diaphragm beneath the chain to the upper edge of the square mouth, and another plate extending from the rear edge of the square mouth to the lower edge of said diaphragm. 70

5. In a suction dredge of the character described; an arm adapted to be raised and lowered; a suction pipe carried on the inside of said arm and terminating in a nozzle with a mouth near the lower end of the arm, 75 said nozzle being substantially square in cross section and the side edges of the same being rounded; a chain screen carried by said arm and having its lower bight mounted on disk wheels adjacent the sides of the nozzle whereby the chain is adapted to move across the mouth of the nozzle; and means for preventing stones from lodging between the chain and the nozzle, said means comprising side plates on the arm, a diaphragm 80 in the arm surrounding the suction pipe and extending between the two reaches of the chain, a curved plate extending from the upper edge of the diaphragm beneath the chain to the upper edge of the square mouth, 85 and another plate extending from the rear edge of the square mouth to the lower edge of said diaphragm. 90

6. In a suction dredge of the character described; an arm adapted to be raised and lowered; a suction pipe carried on the inside of said arm and terminating in a nozzle with a mouth near the lower end of the arm, said nozzle being substantially square in cross section and the side edges of the same being 95 rounded; a chain screen carried by said arm and having its lower bight mounted on disk wheels adjacent the sides of the nozzle whereby the chain is adapted to move across the mouth of the nozzle; a diaphragm in the arm extending downwardly to the lower reach of the chain; and a plate lying above the lower reach of the chain extending from the rear edge of the nozzle to the lower edge of said diaphragm, said plate, said diaphragm, and said disk wheels serving to exclude stones from the space under the nozzle between the nozzle and the lower reach of the chain. 100

7. In a suction dredge of the character described; an arm adapted to be raised and lowered; a suction pipe carried by the arm and terminating in a nozzle with a mouth at the lower end of the arm; a chain screen carried by the arm and having its bight lying 115 across the mouth of the nozzle; and means boxing in the nozzle between the two reaches of the chain adjacent the mouth of the nozzle, whereby stones are excluded from the spaces above and below the nozzle between 120 the nozzle and the reaches of the chain. 125

8. In a suction dredge of the character described; an arm adapted to be raised and lowered; a suction pipe carried by the arm and terminating in a nozzle with a mouth at 130

the lower end of the arm; a shaft mounted on the lower end of the arm; a pair of disk wheels mounted on said shaft at the sides of the nozzle with their peripheries adjacent to the mouth of the nozzle; a chain screen carried by the arm and having its lower bight lying over said wheels, whereby said chain screen will lie across the mouth of the nozzle; and means for supporting said nozzle from the aforementioned shaft.

9. In a suction dredge of the character described; an arm adapted to be raised and lowered; a suction pipe carried on the inside of said arm and terminating in a nozzle with a mouth near the lower end of the arm, said nozzle being substantially square in cross section and the side edges of the same being rounded; a chain screen carried by said arm and having its lower bight mounted on wheels adjacent the sides of the nozzle, whereby the chain is adapted to move across the mouth of the nozzle; and a plate lying over the lower reach of the chain and extending backwardly and upwardly in said arm from the rear edge of the mouth of the nozzle.

In witness whereof, I have hereunto set my hand, this 24th day of March, A. D. 1927.

OSCAR W. ANDERSEN.
